UNITED STATES PATENT OFFICE

159,020

LIPSTICK HOLDER

Albert E. Vaughn, Orange, N. J.

Application July 25, 1949, Serial No. 4,107

Term of patent 14 years

(Cl. D86—10)

To all whom it may concern:

Be it known that I, Albert E. Vaughn, residing at Orange, in the county of Essex, State of New Jersey, have invented a new, original, and ornamental Design for a Lipstick Holder, of which the following is a specification, reference being had to the accompanying drawing, forming part thereof, in which:

Fig. 1 is a perspective view of the lipstick holder, showing my new design, as viewed from one side thereof;

Fig. 2 is a perspective view of the holder, as observed from the opposite side thereof;

Fig. 3 is an end view of the holder, as observed from the left in Fig. 1;

Fig. 4 is an end view of the holder, as viewed from the right in Fig. 1; and

Fig. 5 is a plan view of the holder in extended condition.

I claim:

The ornamental design for a lipstick holder, substantially as shown.

ALBERT E. VAUGHN.
